UNITED STATES PATENT OFFICE.

JEAN VAN OOSTERWYCK, OF LONCIN-ANS, BELGIUM.

WATER-TUBE BOILER.

1,398,943.

Specification of Letters Patent. Patented Nov. 29, 1921.

Application filed March 25, 1913. Serial No. 756,754.

(GRANTED UNDER THE PROVISIONS OF THE ACT OF MARCH 3, 1921, 41 STAT. L., 1313.)

To all whom it may concern:

Be it known that I, JEAN VAN OOSTERWYCK, engineer, a subject of the King of the Belgians, and resident of 45 Rue de 5 Bruxelles, at Loncinc-Ans, Belgium, have invented certain new and useful Improvements in and Relating to Water-Tube Boilers.

In known water tube boilers it is impossible to obtain energetic evaporation without a great deal of priming, as the resistance of the water forces the steam bubbles to collect at certain places in the boiler and the said steam cushions or pockets become detached in jerks which raise the mass of water. These phenomena bring about priming. This spasmodic action prevents water from circulating on the heated walls, which is a disadvantage and a danger.

20 This invention relates to a multi-tubular boiler characterized by the fact that:

1. The complete cycle of circulation, up to the evolution of steam, is constituted by several closed circuits which makes it possible to generate a much greater quantity 25 of steam than any other known boiler of the same volume, and at the same time to obtain absolutely dry steam.

2. The water is taken in the boiler at 30 gradually higher and higher levels, circulates through elements of a volume successively decreasing as they approach the furnace, which renders the evaporation very energetic.

35 3. Only the element nearest to the furnace is capable of taking up the radiation of the furnace, and evolves its steam above the level of water in the boiler through a large number of conduits of small diameter. These 40 numerous conduits act so as to dissociate the large steam pockets which collect in the upper portion of the element nearest to the furnace, which insures the production of dry steam.

45 4. The conduits which evolve or disengage, above the level of water, the steam coming from the header which is nearest to the furnace, can be formed either by small tubes riveted to said header or by large tubes 50 riveted to the header in question and containing either several concentric tubes, the diameters of which are more and more reduced toward the center, or by numerous juxtaposed tubes of small diameter, or longitudinal partitions, or any other kind of sub-

divisions intended to prevent large steam pockets from forming.

A construction of a boiler according to this invention is illustrated by way of example, in the accompanying drawings in 60 which:

Figure 1 is a longitudinal section of the boiler.

Fig. 2 a perspective view of the boiler.

Fig. 3 a partial longitudinal diagrammatic section of the boiler, showing the method of formation of steam.

Fig. 4 is a cross-section of a tube of large diameter for disengaging the steam, this tube containing many concentric tubes 70 provided with openings of any shape, irregularly distributed and the diameters of which decrease respectively toward the center.

Fig. 5 is a cross-section of a tube of large diameter for disengaging steam and containing numerous juxtaposed tubes of small diameter, and

Fig. 6 is a cross-section of a tube of large diameter for disengaging steam, containing longitudinal partitions.

In Fig. 1 the furnace is marked 1.

In Figs. 1 and 2, groups of oblique tubes of heating surface of volume gradually decreasing toward the furnace, are marked respectively 2, 3, 4, 5. Headers are marked 85 6, 7, 8, 9, 10, 11. The water and steam drum is marked 12. The header 6 is supplied with the coolest water from the drum 12 by means of a feed tube 13. Hot water from the header 7 is discharged into the 90 tank 12 by means of tubes 14. The header 8 is fed with hotter water than that supplied to the header 6, by a tube 15. Very hot water is discharged into the tank 12 by means of discharge tubes, one of which 95 is marked 16. The header 10 is supplied with still hotter water than that supplied to the header 8, by feed tubes 17. Certain of the numerous tubes for disengaging dry steam, of small diameter, are marked 18.

100 In Fig. 1: 19, 20, 21 and 22 are baffle plates, and 23, 24, 25, 26 are arrows showing the path of the gases.

In Figs. 1 and 2, 27 indicates the surface 105 of water.

In Fig. 3: 1, 5, 10, 11, 12, 17, 18 and 27 correspond to the parts shown in the preceding figures and marked with similar reference numbers. 28 shows the water of the drum 12. 29 is the water of the central 110

layer of the volume 28 descending by gravity in the feed tube 17. 30 is water coming from 29 and strongly heated in the tubes 5 which are quite close to the furnace 1. 31 5 is very hot water contained in the header 11. 32 is a large steam bubble occupying the upper portion of the header 11. 33 are small steam bubbles dissociated by the small diameter of the discharge tubes 18 10 and drawn energetically toward the upper portion of the drum 12.

In Fig. 4, 18 is a tube of large diameter for disengaging dry steam. 34, 34', 34², 34³, 34⁴, 34⁵ are concentric tubes of 15 diameters which decrease toward the center.

In Fig. 5, 18 is a tube for disengaging dry steam. 35, 35', 35², 35³, 35⁴ are numerous juxtaposed tubes of small diameter.

In Fig. 6, 18 is a tube of large diameter 20 for disengaging dry steam 36, 36', 36², 36³ are longitudinal partitions having for their purpose to destroy large steam pockets, this being also the function of the concentric tubes 34, 34', 34², 34³, 34⁴, 34⁵ and of the 25 juxtaposed tubes 35, 35', 35², 35³.

In Figs. 4, 5 and 6, the numbers 37, 37 . . . 37 indicate openings of any suitable shapes and dimensions made on any suitable parts of the partitions, in order to 30 facilitate the disengagement of steam.

The lowest layer, that is to say, the densest and the coolest layer of the water contained in the drum 12, escapes through the series of feed tubes 13, arrives at the header 35 6, passes through the groups of tubes similar to 2 and 3, then through the header 7 in order to rise again into the drum 12 through series of tubes similar to 14.

Water from a layer hotter than the first, 40 escapes from the tank 12 through the series of feed tubes 15, arrives at the header 8, passes through groups of tubes similar to 4, then through the header 9, in order to rise again into the drum 12 through series 45 of tubes similar to 16.

Water from the upper layer, that is to say, the hottest water in the tank 12, escapes through the series of feed tubes 17, arrives at the header 10, passes through the 50 groups of tubes similar to 5, then through the header 11 in order to rise again into the drum in the form of steam through the series of tubes similar to 18.

The very small diameter of the latter 55 tubes brings about the division of the steam pockets accumulated at the top of the header 11, without any spasmodic rising, which allows the steam to be energetically generated without priming.

60 Obviously the number of headers and groups of tubes, either descending or oblique or ascending, can be of any suitable number.

The diagrammatic Fig. 3, showing the 65 generation of steam, shows clearly one of

the characteristics of the invention. Owing to the small diameter of the numerous discharge or disengagement tubes 18, the large steam bubbles having the tendency to form at 32, are dissociated and divided into a 70 large number of steam bubbles which actively escape through the small tubes 18, without meeting therein masses of water which interfere with their rise.

This peculiarity renders possible an energetic 75 disengagement which is very favorable to the production of large quantities of dry steam.

Having now fully described my said invention, what I claim and desire to secure 80 by Letters Patent is:

1. In a multitubular boiler, having a plurality of tube bunches, front and rear headers which are independent of each other, said tube bunches being united by said headers into elements equally independent of each other, the heating surface of said independent bunches decreasing gradually toward the fire-grate.

2. In a multitubular boiler, having a plurality of tube bunches which are independent of each other, front and rear headers which connect said tube elements into independent elements, a water and steam drum having conduits connecting it with each of 95 said elements, said conduits ending the higher inside the drum the farther said elements are situated from the drum, the heating surface of said independent elements decreasing gradually toward the fire-grate. 100

3. In a multitubular boiler having a plurality of tubes forming groups which are independent of each other, a front and a rear header for each independent group of tubes, said headers being just large enough to 105 unite each of said groups, a steam and water drum, ascending conduits connecting said headers with the steam and water drum and ending the higher inside said drum, the nearer the corresponding headers are to the 110 fire-grate, the heating surfaces of the said groups gradually decreasing toward the fire-grate.

4. In a multitubular boiler, having a plurality of tubes forming groups which are 115 independent of each other, front and rear headers for each independent group of tubes a water and steam drum, connecting each header with said drum, said means terminating inside said drum at levels which are 120 the higher the farther off the corresponding tube group is away from said drum, the heating surface of said groups decreasing successively toward the fire-grate, said means feeding the upper group through the 125 upper part of its rear-header and each one of the lower headers through its lower part and said means also discharging the contents of each front-header through its upper part.

5. In a multitubular boiler, having a drum and inclined tubes, divided into independent groups one above the other, a front and rear header for each group, feeding conduits and discharge conduits for each of said headers, said conduits terminating inside the drum at successively higher levels; the heating surfaces of each independent group successively decreasing toward the fire-grate, the conduits for the lowermost front header being subdivided into longitudinal passages ending inside the drum above the normal water level. 6. In a multitubular boiler, having a drum and inclined tubes, divided into independent groups one above the other, a front and rear header for each group, feeding conduits and discharge conduits, for each of said headers, said conduits terminating inside the drum at successively higher levels; the heating surfaces of each independent group successively decreasing toward the fire-grate, the conduits for the lowermost front header being subdivided into longitudinal passages ending inside the drum above the normal water level, 25 said passages being intercommunicating. 7. In a multitubular boiler having a drum and inclined tubes divided into independent groups one above the other, a front and rear header for each group, feeding conduits and discharge conduits for each of said headers, said conduits terminating inside the drum at successively higher levels; the heating surfaces of each independent group successively decreasing toward the fire-grate, the conduits for the lowermost front header comprising a plurality of main pipes, each of said main pipes inclosing a plurality of smaller pipes of the same length, each of said smaller pipes having perforations, the lowermost front header being situated beyond the direct action of the flame of the fuel and baffle plates between the tubes forming the independent groups, to guide the gases of combustion. 8. In a multitubular boiler having a drum and inclined tubes divided into independent groups one above the other, a front and rear header for each group, feeding conduits and discharge conduits for each of said headers, 40 said conduits terminating inside the drum at successively higher levels; the heating surfaces of each independent group successively decreasing toward the fire-grate; the tubes in one of said groups being staggered. 9. In a multitubular boiler having a drum and inclined tubes divided into independent groups one above the other, a front and rear header for each group, feeding conduits and discharge conduits for each of said headers, 45 said conduits terminating inside the drum at successively higher levels; the heating surfaces of each independent group successively decreasing toward the fire-grate, the tubes in the lowermost group being staggered. 10. In a multitubular boiler having a drum and inclined tubes divided into independent groups one above the other, a front and rear header for each group, feeding conduits and discharge conduits for each of said headers, 50 said conduits terminating inside the drum at successively higher levels; the heating surfaces of each independent group successively decreasing toward the fire-grate, the conduits for the lowermost front header comprising a plurality of main pipes, each of said main pipes inclosing a plurality of smaller pipes of the same length, each of said smaller pipes having perforations, the lowermost front header being situated beyond the direct action of the flame of the fuel and baffle plates between the tubes forming the independent groups, to guide the gases of combustion. 11. In a multitubular boiler having a drum and inclined tubes divided into independent groups one above the other, a front and rear header for each group, feeding conduits and discharge conduits for each of said headers, said conduits terminating inside the drum at successively higher levels; the heating surfaces of each independent group successively decreasing toward the fire-grate, the conduits for the lowermost front header comprising a plurality of main pipes, each of said main pipes inclosing a plurality of smaller pipes of the same length, each of said smaller pipes having perforations, the lowermost front header being situated beyond the direct action of the flame of the fuel and baffle plates between the tubes forming the independent groups, to guide the gases of combustion. 12. In a multitubular boiler, having a plurality of tubes forming groups which are independent of each other, front and rear headers for each independent group of tubes, a water and steam drum, connecting each header with said drum, said means terminating inside said drum at levels which are the higher the farther off the corresponding tube group is away from said drum, the heating surface of said groups decreasing successively toward the fire-grate, said means feeding the upper group through the upper part of its rear header and each one of the lower headers through its lower part and said means also discharging the contents of each front-header through its upper part and baffle plates between the tubes forming the independent groups to guide the combustion gases. The foregoing specification signed at 115 Brussels this fourteenth day of March, 1903. JEAN VAN OOSTERWYCK. In presence of— E. HEYLE, CHAS. ROY NASMITH.
